Term of patent 14 years

(Cl. D13—1)

FIG. 1

FIG. 2

FIG. 3

FIG. 4

FIG. 1 is a front perspective view of a combined telephone enclosure and support showing our new design; and

FIGS. 2, 3, and 4 are rear, top, and side views, respectively, to an enlarged scale, of the combined telephone enclosure and support.

The phone is shown in broken lines in FIG. 1 for illustrative purposes only. The dominant features of our design reside in the portions shown in full lines.

We claim:

The ornamental design for a combined telephone enclosure and support, as shown and described.
